DESIGN.

—o—
J. L. FOLSOM.

CARPET.

No. 18,127.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,127, dated March 6, 1888.

Application filed January 26, 1888. Serial No. 262,048. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein 15 specifically shown and claimed.

The accompanying photograph is a face view 15 of a carpet showing my new design.

My design consists of an assemblage of geometrical flower forms, generally circular in shape and closely repeated over the face of the

carpet, as shown. At the center of these flower forms are square or diamond shaped ornaments 20 of a geometrical character. The leaves of these figures are built up with a sort of block-work giving the figures an irregular rectangular outline. These flower forms touch and overlie one another, making a continuous mass of 25 flower-work, with here and there a little irregular block-work intervening.

What I claim as new, and desire to secure by Letters Patent, is—

The design for carpets, consisting of the design substantially as shown.

JAS. L. FOLSOM.
